Primary Examiner — Mimosa De

(74) Attorney, Agent, or Firm — Greg M. Popowitz;
 Assouline & Berlowe, P.A(57) **CLAIM**

The ornamental design for a unitary swivel, as shown and described.

DESCRIPTION

FIG. 1 is a front perspective view of a first embodiment of a unitary swivel.

FIG. 2 is a rear perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof.

FIG. 8 is a back view thereof.

FIG. 9 is a front perspective view of a second embodiment of a unitary swivel.

FIG. 10 is a rear perspective view thereof.

FIG. 11 is a top view thereof.

FIG. 12 is a bottom view thereof.

FIG. 13 is a left side view thereof.

FIG. 14 is a right side view thereof.

FIG. 15 is a front view thereof; and,

FIG. 16 is a back view thereof.

The illustrative broken lines depict environmental subject matter that form no part of the present claimed design.

FIGS. 2-8 and 10-16 are shown in enlarged scale, without environmental structure for ease of illustration.
